UNITED STATES PATENT OFFICE.

STERLING L. BAILEY, OF HYDE PARK, ILLINOIS.

VENTILATION OF BUILDINGS.

SPECIFICATION forming part of Letters Patent No. 398,874, dated March 5, 1889.

Application filed January 7, 1889. Serial No. 295,603. (No model.)

To all whom it may concern:

Be it known that I, STERLING L. BAILEY, a citizen of the United States, residing in Hyde Park, in the county of Cook and State of Illinois, have invented a new and useful Improvement in Ventilation of Buildings, of which the following is a specification.

What is known as the "Smead Dry-Closet System" is now quite largely in use, more especially in public-school buildings in the United States. Generally stated, this dry-closet system of Mr. Smead consists in providing the building—generally in the basement—with a privy consisting of a series of seats which open into a horizontal air shaft or passage, so that the fecal matter is dropped upon the bottom of this shaft, where it is speedily dried, much reduced in bulk, and rendered innocuous by a current of air made to pass through the said horizontal shaft and in contact with said fecal matter. For this purpose the foul air from the building is made use of by connecting one end of the horizontal privy-shaft to the foul-air outlets of the building and the other end of said horizontal shaft to a vertical stack or ventilating-chimney carried up high enough to produce the necessary draft. Unless there be a constant upward current in this ventilating-stack, it may happen under certain conditions that the ventilation of the building will be checked, and even, under some circumstance, the current reversed and the contaminated air from the privy-shaft brought into the rooms. For this reason it has frequently been found necessary or desirable to apply to the ventilating-stack some additional means for producing and insuring a constant upward current in said stack. Such means has been ordinarily an independent stove, and it has also been suggested to use in this place a fan. Either of these devices will serve the desired purpose, but requires special management and continued attention in addition to the objection of cost, &c. In the present invention I propose to make the ventilating-stack constant and certain in its action by a very simple and inexpensive means, as follows: It is usual in the construction of these ventilating-stacks to embody in the structure of the stack, in addition to the large ventilating-flue, a smaller smoke

flue or flues for the purpose of carrying off the smoke and products of combustion from and giving draft to the furnace or heating apparatus of the building. A metallic smoke-pipe 55 is commonly led from the furnace or other heating apparatus, and I propose in the present invention to utilize the heat of this metallic smoke-pipe to give the necessary draft to the ventilating-flue, and this I accomplish 60 by surrounding such metallic smoke-pipe with an air-pipe which leads into the ventilating-flue, or, what would be virtually the same thing in many respects, inclosing such an air-pipe within the smoke-pipe, the air-pipe in both 65 cases leading, of course, into the ventilating-flue and the smoke-pipe into the separate smoke-flue.

In the accompanying drawings, which form a part of this specification, and in which similar letters of reference indicate like parts, Figure 1 is a sectional view of a building provided with my invention. Figs. 2, 3, and 4 are horizontal sections of modified forms of the ventilating and smoke flues, the heating 75 apparatus, and the air and smoke pipes. Figs. 5, 6, and 7 are vertical sections, respectively, on the lines 5 5, 6 6, and 7 7 of Fig. 2.

In said drawings, A A represent the rooms of the building to be ventilated. 80

B is the basement.

C C C, &c., are the closets.

D is the horizontal air-shaft beneath the closets; d, the entrance for the air to said horizontal shaft; d', the exit for the air from 85 said horizontal shaft leading into the vertical ventilating-shaft E.

F is the smaller or smoke flue, usually built in one structure with the ventilating-shaft, the entire structure constituting the ventilating and smoke stack of the building. 90

G is the furnace or heating apparatus, provided with a smoke-pipe, H, leading from the furnace to the smoke-flue F.

J is the air-pipe surrounding the smoke-pipe, open at j to receive air from the basement, and delivering the same at j' into the ventilating-shaft E. 95

A flaring or funnel-shaped mouth may be applied at j with good effect. 100

I find that the heat of the smoke-pipe thus utilized will give a steady and constant cur-

rent in the ventilating-shaft, requiring no special attention; that all danger of stoppage of ventilation or a reverse of the foul-air currents is thus obviated, and that the cost 5 of the necessary apparatus requiring to be added is so slight as to be inconsiderable.

At Fig. 2 the apparatus is shown as applied to a stack where the air-pipe and smoke-pipe enter side by side, the apparatus being otherwise as shown at Fig. 1. The modification at Fig. 3 consists in making the outer or air pipe perforated with holes to receive air at many points. In the modification shown at Fig. 4 the air-pipe is shown inclosed within the 15 smoke-pipe, which is somewhat enlarged for the purpose of receiving it. In this latter figure the draftsman, for convenience of illustration, has shown the inlet or mouth of the air-pipe as extending horizontally from the 20 side. A better construction would indicate this opening as extended downward instead of laterally.

I claim—

1. In a ventilating apparatus for buildings, the combination, with the dry-closets and 25 their horizontal shaft D, of the ventilating-shaft E, the smoke-flue F, the furnace G, and the smoke-pipe H, connecting with the smoke-flue F, and the air-pipe J, heated by the smoke-pipe and communicating with the ventilating-shaft E, substantially as specified.

2. In a building to be ventilated, the combination of the heating apparatus G, flues E and F, smoke-pipe H, connected to the flue F, and air-pipe J, heated by the smoke-pipe and 35 connected to the ventilating-flue E, substantially as specified.

STERLING L. BAILEY.
